(57) **CLAIM**

The ornamental design for a fluorometer, as shown and described.

DESCRIPTION

FIG. 1 is a front perspective view of a first embodiment of a fluorometer;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a second front perspective view thereof;

FIG. 9 is a front perspective view of a second embodiment of a fluorometer;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a second front perspective view thereof.

The broken lines in the Figures show portions of the fluorometer that form no part of the claimed design.
